FIRE EXTINGUISHER

Charles L. Adams, Cape May, N. J.

Application March 9, 1938, Serial No. 194,954

2 Claims. (Cl. 169—26)

This invention relates to fire extinguishers, and more particularly to fire extinguishers of the portable type.

The primary object of the invention is to provide a fire extinguisher which will automatically operate with the rise in the temperature caused by fire, to the end that fire extinguishing liquid will be released, extinguishing the fire.

Another important object of the invention is to provide a fire extinguisher of the portable type having a valve which may be manually operated to release the extinguishing liquid, should it be desired to remove the fire extinguisher from its hanger for use in the hands of the operator in extinguishing a fire.

A still further object of the invention is the provision of a valve held in place by a fusible plug, the construction of the valve being such that the fusible plug may be readily and easily replaced to reset the valve, by persons unfamiliar with mechanics.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a longitudinal sectional view through a fire extinguisher constructed in accordance with the invention.

Figure 2 is a fragmental sectional view through the extinguisher, illustrating the valve as moved to release the extinguishing liquid contained in the tank or body portion of the extinguisher.

Referring to the drawing in detail, the tank or body portion of the extinguisher is indicated generally by the reference character 5, and as shown, the tank is provided with a neck 6 formed with internal threads to accommodate the valve proper 7.

This valve 7 comprises a hollow body portion 8 formed with an annular flange 9 disposed at its outer end. The outer end of the body portion 8 is formed with internal threads to receive the removable plug 10 of the valve, so that the removable plug may be readily and easily positioned or removed from the body portion 8. The plug 10 is also formed with an annular flange 11 that has its periphery knurled so that it may be readily gripped by the operator to rotate the

plug. The flanges 9 and 11 are formed with openings adapted to register for the reception of a sealing wire 12, which is of a construction to be readily destroyed and removed by a tool such as a screwdriver or the like.

A bore is formed longitudinally of the removable plug 10, and is of a diameter to accommodate the valve stem 13 which is hollow, the outer end thereof, being open. Openings 14 are formed in the valve stem 13 near the outer end of the valve stem, and afford means whereby the fire extinguishing liquid passing into the hollow valve stem 13, may be discharged therefrom. Openings indicated by the reference character 15 establish communication between the hollow valve stem 13 and interior of the valve body 8, to the end that fire extinguishing liquid passing into the hollow body portion 8, may pass into the hollow valve stem 13.

Formed on the inner end of the valve stem 13, is the valve head 16 which is tapered to fit into a tapered opening or valve seat formed in the inner end of the valve body portion 8, as shown by Figure 1 of the drawing.

The bore formed in the removable plug 10, is enlarged at its outer end, for the reception of the fusible member 17, which is positioned against the outer end of the valve stem 13 holding the valve stem and valve head 16 in their active positions, to prevent the flow of fire extinguishing liquid from the tank or body portion 5, under normal conditions.

The reference character 18 designates a threaded tubular member fitted in the enlarged portion of the bore of the removable plug. Openings 19 are formed in the wall of the tubular member 18 at a point above the outer end of the tubular member, so that when the fusible member 17 melts or is destroyed by the heat caused by a fire, the valve stem 13 will move downwardly, the outer end of the valve stem resting against the cap 20 that closes the outer end of the tubular member 18, allowing the fire extinguishing liquid to exhaust through the openings 19.

In order that the valve 7 will be held in its proper adjusted position within the neck of the tank 5, a set screw 21 is provided, which extends through the neck 6, contacting with the inner end of the valve.

From the foregoing it will be seen that due to the construction shown and described, the fire extinguisher forming the subject matter of the present invention, may be supported in any desirable position, by the usual bracket, the construc-

tion of the valve being such that the valve will automatically operate to release the fire extinguishing liquid, under abnormal heat. It will of course be understood that the fire extinguishing liquid when placed in the tank or body portion of the device, is under pressure, to operate the valve, when the fusible material is dissipated by the abnormal heat.

Should it be desired to use the extinguisher as 10 a portable or hand device, it may be readily removed from its hanger and the plug closing the outer end of the valve body, removed or loosened sufficiently to allow the valve to disengage its seat, releasing the fire extinguishing liquid.

15 I claim:

1. In a portable automatic fire extinguisher, a tank, a hollow valve body mounted in the mouth of the tank, and having a valve seat, a valve member normally closing the valve seat, a hollow valve stem carrying a valve at its inner end and adapted to normally close the valve seat, said valve stem having openings whereby fire extinguishing liquid may pass from the valve stem, a plug removably held in one end of the 25 hollow valve body, a fusible member held by

the plug and against which said valve stem engages and said valve adapted to move to its open position releasing fire extinguishing material when the plug is rotated in one direction, or when the fusible member melts.

2. A fire extinguisher comprising a tank, a hollow valve member removably mounted in the mouth of the tank and having a valve seat, a removable plug extending into the hollow valve member and having a threaded bore, a hollow 10 valve stem operating through the hollow valve member and having openings adjacent to the inner and outer ends thereof, a valve on the inner end of the valve stem and normally engaging the valve seat closing the tank, a tubular member fitted in the threaded bore and having openings, a plug of fuseable material fitted in the hollow valve member and against which one 15 end of the valve stem engages, and said valve stem adapted to move into the tubular member unseating the valve and releasing fire extinguishing liquid through the openings when the fuseable material burns.

CHARLES L. ADAMS. 25
